US00D755946S

(12) **United States Design Patent**
Arai et al.

(10) **Patent No.:** US D755,946 S
(45) **Date of Patent:** ** May 10, 2016

(54) **PROPELLER FAN**

(71) Applicant: **MITSUBISHI ELECTRIC CORPORATION**, Tokyo (JP)

(72) Inventors: **Toshikatsu Arai**, Tokyo (JP); **Hitoshi Kikuchi**, Tokyo (JP); **Tsutomu Takahashi**, Tokyo (JP); **Tatsushi Murakami**, Tokyo (JP); **Hiromichi Aoki**, Tokyo (JP); **Tomoya Fukui**, Tokyo (JP)

(73) Assignee: **Mitsubishi Electric Corporation**, Tokyo (JP)

(**) Term: **15 Years**

(21) Appl. No.: **29/543,180**

(22) Filed: **Oct. 21, 2015**

CPC F04D 29/326; F04D 29/329; F04D 29/38; F04D 29/382; F04D 29/384; F04D 29/386; F04D 29/388; F04D 29/281; F04D 29/282; F04D 29/28; F04D 29/663; B63H 23/34; B63H 1/20
